DESIGN FOR A HANDBAG OR SIMILAR ARTICLE

Fred G. Ungar, New York, N. Y.

Application November 21, 1945, Serial No. 123,956

Term of patent 7 years

(Cl. D87—3)

To all whom it may concern:

Be it known that I, Fred G. Ungar, a citizen of the United States of America, residing in New York city, county of New York, and State of New York, have invented a new, original, and ornamental Design for a Handbag or Similar Article, of which the following is a specification, reference being had to the accompanying drawing, forming part thereof.

Fig. 1 is a front perspective view of a handbag or similar article, showing my new design.

Fig. 2 is a rear view thereof.

Fig. 3 is a front perspective view with the flap portion in open position illustrating the handbag closure.

The dominant feature of my design resides in the portions shown in solid lines.

I claim:

The ornamental design for a handbag or similar article, substantially as shown and described.

FRED G. UNGAR.
